DESIGN FOR A BOOT JACK

Thomas L. Hauret, Los Angeles, Calif.

Application October 8, 1945, Serial No. 122,665

Term of patent 7 years

(Cl. D7—3)

To all whom it may concern:

Be it known that I, Thomas L. Hauret, a citizen of the United States, residing at Los Angeles, county of Los Angeles, State of California, have invented a new, original, and ornamental Design for a Boot Jack, of which the following is a specification, reference being had to the accompanying drawing, forming a part thereof.

Fig. 1 is a plan view of a boot jack showing my new design;

Fig. 2 is a side elevation thereof;
Fig. 3 is an end elevation taken from the right end of Fig. 2; and

Fig. 4 is an end elevation taken from the left end of Fig. 2.

I claim:

The ornamental design for a boot jack, substantially as shown.

THOMAS L. HAURET.
